(57) **CLAIM**

The ornamental design for a wheel, as shown and described.

DESCRIPTION

The present application is related to copending application Ser. No. 29/491,722, entitled Autonomous Vehicle Overall

Exterior, to application Ser. No. 29/491,723, entitled Autonomous Vehicle Door, to application Ser. No. 29/491,734, entitled Autonomous Vehicle Headlamp, to application Ser. No. 29/491,730, entitled Autonomous Vehicle Taillamp, to application Ser. No. 29/491,726, entitled Autonomous Vehicle Wing Assembly, and to application Ser. No. 29/491,727, entitled Autonomous Vehicle Rear Vent/Reflector, each of which is filed concurrently herewith, the entire disclosures of which are incorporated by reference herein.

FIG. 1 is a front perspective view of a wheel according to a first embodiment of our design;

FIG. 2 is a front elevation view thereof;

FIG. 3 is a right side elevation view thereof;

FIG. 4 is a left side elevation view thereof;

FIG. 5 is a top elevation view thereof;

FIG. 6 is a bottom elevation view thereof;

FIG. 7 is a front perspective view of a wheel according to a second embodiment of our design;

FIG. 8 is a front elevation view thereof;

FIG. 9 is a right side elevation view thereof;

FIG. 10 is a left side elevation view thereof;

FIG. 11 is a top elevation view thereof;

FIG. 12 is a bottom elevation view thereof;

FIG. 13 is a front perspective view of a wheel according to a third embodiment of our design;

FIG. 14 is a front elevation view thereof;

FIG. 15 is a right side elevation view thereof;

FIG. 16 is a left side elevation view thereof;

FIG. 17 is a top elevation view thereof;

FIG. 18 is a bottom elevation view thereof;

FIG. 19 is a front perspective view of a wheel according to a fourth embodiment of our design;

FIG. 20 is a front elevation view thereof;

FIG. 21 is a right side elevation view thereof;

FIG. 22 is a left side elevation view thereof;

FIG. 23 is a top elevation view thereof; and,

FIG. 24 is a bottom elevation view thereof.

The broken line showing of a tire, center cap and valve stem hole is included for the purpose of illustrating such environmental components and forms no part of the claimed design.

(Continued)

The stipple shading and the straight line shading in FIGS. 13-14 and 19-20 illustrate a contrasting appearance.
